8 Claims**ABSTRACT OF THE DISCLOSURE**

An insole shaped insert used with a conventional last during a lasting operation, and a method of making a shoe using such an insert. The insert has a surface contoured for mating engagement with the sole surface of a last and an opposite surface contoured to conform to the bottom surface of the insole to be inserted in the finished shoe.

BACKGROUND OF THE INVENTION

The present invention relates to the manufacture of contoured insole shoes, and more particularly to an insert for use in combination with a standard shaped last for use in such manufacture, wherein the contoured insole is inserted into the partially completed shoe after the shoe is removed from the last.

In recent years, the contoured insole shoe has met with great acceptance, particularly in the service and dress shoe field. Heretofore, these shoes have generally been constructed by conventional shoemaking methods, with the contoured insole being applied to a last in lieu of a non-contoured or flat insole, and the shoe being constructed on the contoured insole which remains as part of the shoe when removed from the last. As may be envisioned from the foregoing description of this customary manufacturing process, a last having modified structure from that of a standard last is necessary to accommodate the contour surface of the insole during shoe construction. For a manufacturer to get into the contour insole field therefore, it is necessary first to obtain lasts of modified construction, to accommodate this shoe construction.

With the increase in popularity of the contour insole shoe, many manufacturers have been forced into purchasing a complete set of lasts to accommodate these shoes, the lasts being of such modified structure that they are capable of only accommodating shoes built on a contoured insole. Thus, the investment in new lasts to enter the contour insole field involves somewhat of a risk in that a possibility exists that the lasts will only be subjected to limited use during normal plant operation by a manufacturer, and the entire line of lasts may be made obsolete should the popularity of the contour insole wane.

A primary object of the invention therefore, is to allow a shoe manufacturer to proceed conventionally in the manufacture of contoured insole shoes without the problems and hazards connected with special lasting, welt rib attaching, heel seat treatment, etc., which are involved when contour insoles are built in as part of the lasted shoe.

A second object of the invention is to enable a shoe manufacturer to produce shoes having a contoured insole by employing a standard last used in the manufacture of non-contoured insole shoes.

Another object of the invention is to provide an article which is used in combination with a standard shaped last in the manufacture of contoured insole shoes.

A further object of the present invention is to provide a method of manufacturing contoured insole shoes wherein a standard last is used to construct the shoe.

2

A more general object of the present invention is to facilitate the manufacture of contour insole shoes without the large investment in lasts which have heretofore been necessary, by enabling the manufacturer to temporarily modify a standard last for manufacturing contoured insole shoes, after which the last may be again used for standard shoe construction.

SUMMARY OF THE INVENTION

To achieve the objects of the present invention, as set forth, an article of manufacture is provided having its one surface conforming generally to the sole surface of a standard last, and its opposite surface conforming generally to the sole surface of a contoured insole to be used in the shoe construction. The article generally comprises a forepart and a back part hingedly connected one to the other. The hinged construction permits the use of the article with a standard two-part last having a forward portion and a heel portion which are opened to facilitate removal of the shoe from the last.

In the method aspect, the forepart of the article is generally attached in a temporary manner such as by tacks, staples, etc., to the forward portion of the last and the back part of the article is rested, without fastening, on the heel portion of the last. A shoe of standard construction, with exception of the insole, is now constructed on the last and article combination. When the construction is complete, the last is opened and the shoe removed, after which a contoured insole is inserted in the shoe.

BRIEF DESCRIPTION OF THE DRAWINGS

FIG. 1 is a plan view of an article of manufacture for use in combination with a standard last, and constructed in accordance with the teachings of the present invention;

FIG. 2 is a sectional view taken along the line II—II of FIG. 1 showing details of the article taken on an enlarged scale for clarity;

FIG. 3 is an elevational view, partially in section, showing the article attached to a standard last;

FIG. 4 is a sectional elevational view similar to FIG. 3, showing a shoe construction manufactured on the last structure shown in FIG. 3, just prior to removal from the last;

FIG. 5 is an elevational view similar to FIG. 4, showing the last and article combination in its open position during removal of the shoe structure therefrom;

FIG. 6 is a sectional elevational view of a contoured insole to be used in the shoe structure of FIGS. 4 and 5, showing the article of FIGS. 1 and 2 superimposed thereon in phantom lines; and

FIG. 7 is a sectional view taken along the line VII—VII of FIG. 6 showing details of the contoured insole and superimposed article structure, taken on an enlarged scale for clarity.

DESCRIPTION OF THE PREFERRED EMBODIMENT

Referring now to the drawings, in particular FIGS. 1 and 2, there is shown an article of manufacture in the form of a last insert 10 which is constructed to be used in combination with a standard shaped last in the manufacture of contoured insole shoes. The insert 10, shown in plan form in FIG. 1, is of a shape and size to substantially cover the sole portion of the standard last and generally comprises a forepart 11 and a back part 12. The insert 10 is so formed as to have a surface 13 conforming generally to the sole surface of a standard last with which the insert is to be used. The opposite surface 14 is fabricated to conform to the shape of the sole surface of a contoured insole which is to be inserted into a shoe constructed on, and after its removal from, the last. The insert 10 may be fabricated from any known

material which will readily receive fasteners such that a shoe may be manufactured in the standard manner as by tacking a thin sheet of insole material to the insert and the last.

However, it has been found advantageous to manufacture the last insert 10 from a moldable plastic material such as a polyurethane. By providing a mold having the proper contours desired in the insert construction, an inexpensive and semi-rigid structure is produced having the rounded surface contours necessary to conform both to the last sole surface, and the contour insole sole surface. Further, as it is necessary to manufacture an insert 10 for each size of standard last, the use of moldable plastic as an insert material can create a substantial savings in cost over an entire run of insert sizes. A set of molds is thus provided, each corresponding to a different insert size, each of which may be used to produce any given number of inserts 10 which are identical in contour and size, to mate with the appropriate last size.

In the process of forming the insert 10, the mold may be constructed to provide a recessed area onto which a heel plate 15 is fastened. The heel plate 15 serves to take the place of the last heel plate which is covered by the insert 10 during the shoe construction, as will become evident in the description which follows.

Referring still to FIGS. 1 and 2 it will be noted that the forepart 11 and the back part 12 are connected by a hinge 16. While the hinge 16 may take any form which is convenient in fastening the forepart 11 and the back part 12 together, in the insert 10 as shown, the hinge is formed by molding a sheet of canvas cloth, polystyrene plastic, or other flexible material into the insert when it is formed. Thus, the manufacture of the insert as a molded plastic member has the added advantage in that the hinge 16 may be molded into the forepart 11 and the back part 12 to form a unitary structure without the undesirable distortion of the surfaces 13 and 14, resulting from fastening the members together by other methods.

Referring to FIG. 3, there is shown a standard last 17 having a forward portion 18 and a heel portion 19 movable about a hinge point 21 from the closed position (as shown in FIG. 3) to an open position, for removal of the shoe structure therefrom. With the last 17 in the closed position as shown, a sole surface 22 is presented on which the insert 10 is placed in mating engagement, the insert surface 13 having been contoured to correspond to the last sole surface 22 as explained heretofore. The forepart of the insert 10 is now attached to the forward portion 18 of the last 17 by tacks 23, or other suitable fasteners. It will be noted that only the forepart 11 of the insert 10 is attached to the last 17, the back part 12 merely resting on the last. As will be observed in FIG. 3, the hinge line between the forepart 11 and the back part 12 is located approximately at the separation line between the forward portion 18 and the heel portion 19 of the last 17.

With the insert 10 so attached to the last 17, a shoe is constructed on the combination such as is shown in FIGS. 4 and 5. The shoe may be of any well known construction such as a Goodyear welt, cement, lockstitch or any such construction as is well known in the art.

In FIGS. 4 and 5 there is shown a shoe construction 24 built by fastening the component parts upon a thin piece of insole material 26 which is first tacked or otherwise temporarily fastened to the insert 10 in the initial construction of the shoe. The upper 27, outsole 28 and heel 29 are all assembled into the shoe 24 in the usual manner as would be accomplished were the shoe being built upon the last 17 without the insert 10 applied thereto.

Referring now to FIG. 5, with the shoe constructed on the last 17 in the usual manner, the last 17 is opened to provide release of the shoe 24 from the last, the heel end of the shoe being lifted from the heel portion 19 as shown in that figure. It will further be observed in that

figure that the back part 12 of the insert 10 is now free to move relative to the heel portion 19 of the last 17, and folds down upon the heel portion 19 of the last to provide for removal of the shoe 24 from the last 17 in the usual manner. As will be noted in FIG. 5, both the forepart 11 and the back part 12 of the insert 10 are chamfered adjacent the hinge 16 so that a wide range of movement is provided for between the two insert parts.

With the removal of the shoe 24 from the last 18, the insert 10 remains on the last, and another run of contour 10 insole shoes may be made employing the last and insert combination. However, should it be desired to change over to a run of non-contoured insole shoes, the insert 10 is easily removed from the last 18, and, because of its size, requires a relatively small storage space to accommodate it until it is again applied to the last, as hereinbefore described. As will now be noted, the shoe structure 24 is similar in all respects to a shoe manufactured on the standard last 17 without the insert 10, but for a space provided at the sole of the shoe, and a contour in the insole portion of the shoe which has been constructed to receive a contoured shaped insole.

The shoe 24 as now constructed, is provided with an inner sole surface contour 31 which substantially conforms to the surface 14 of the last insert.

In FIGS. 6 and 7 there is shown a contoured insole 33 having a contour surface 34 shaped to conform to the wearer's foot and a sole surface 36. Superimposed on the insole 33, as shown in the phantom lines of FIG. 7, is the last insert 10. As should be evident from these figures, the sole surface 36 of the insole 33 and the sole surface of the insert 10 are identical, while the conforming surface 13 of the insert 10 varies substantially from the contoured surface 34 of the contour insole. The difference in contour between the surface 34 of the insole 33 and the surface 13 of the insert 10 is generally that portion of the standard last which is removed to provide a last on which contoured insole shoes may be fabricated, in prior art shoe construction.

Thus, the thickness dimension of the insert 10 is dictated by the thickness of the insole 33 to be placed in the shoe after removal from the last. The thickness dimension of the insert is such that a shoe manufactured by employing the insert, and having the contoured insole subsequently inserted therein, provides the wearer the proper shoe size corresponding to the standard last size on which the shoe was made.

From the foregoing therefore, it will be appreciated that the various objects of the present invention are accomplished by providing the insert 10 which when used 50 with a standard last to manufacture contoured insole shoes enables a shoe manufacturer to produce contoured insole shoes with a minimum of investment. Additionally, the manufacturer may quickly and easily convert to contoured insole shoe manufacture and back to manufacture 55 of non-contoured insole shoes should the need arise to do so.

While the invention has been shown in but one form, it will be obvious to those skilled in the art that it is not so limited, but is susceptible of various changes and modifications without departing from the spirit thereof.

Having thus described my invention, what I claim as new and desire to secure by Letters Patent of the United States is:

1. An article for use in combination with a last having a standard shaped sole surface in the manufacture of shoes wherein an insole is inserted after the shoe is removed from the last, said article having a surface contoured for mating engagement with the sole surface of the standard last and an opposite surface contoured to conform to the bottom surface of the insole to be inserted in the finished shoe when removed from the last.

2. An article in accordance with claim 1 which is fabricated from a moldable plastic material.

3. An article in accordance with claim 2 wherein said material is a polyurethane plastic.

4. An article for use in combination with a last having a forward portion and a heel portion forming a standard shaped sole surface said portions being movable between an open and a closed position, comprising a forepart and a back part, said forepart having a surface contoured for mating engagement with the sole surface of the last forward portion and said back part having a surface contoured for mating engagement with the sole surface of the last heel portion, the opposite surface of said forepart and the opposite surface of said back part being contoured to conform to the bottom surface of an insole to be inserted in the finished shoe when removed from the last.

5. A method of manufacturing a shoe having a contoured insole on a last having a standard shaped sole surface which comprises the steps of providing an insert member having a first surface contoured for mating engagement with the sole surface of the last and a second surface contoured in accordance with the bottom surface of an insole to be inserted in the shoe when removed from the last, attaching the insert to the last with said first contoured surface engaging the sole surface of the last, assembling components including an upper and an outsole on said last to form a partially completed shoe structure, removing said partially completed shoe structure from said last and inserting a contoured insole in the shoe structure.

6. A method of manufacturing a shoe having a contoured insole on a last comprising a forward portion and a heel portion forming a standard shaped sole surface and movable between an open and a closed position, which comprises the steps of

providing an insert member having a forepart and a back part hingedly connected for relative movement one to the other and a surface contoured for mating engagement with the last sole,

attaching one of said insert parts only to the sole surface of the last,

5

10

15

assembling components including an upper and an outsole on said last to form a partially completed shoe structure,

removing said partially completed shoe structure from the last by opening the last with the insert attached thereto and inserting a contoured insole in the shoe structure.

7. An article for use in combination with a last having a forward portion and a heel portion forming a standard shaped sole surface, said portions being movable between an open and a closed position, comprising a forepart and a back part hingedly connected for relative movement one to the other, said forepart having a surface contoured for mating engagement with the sole surface of the last forward portion and said back part having a surface contoured for mating engagement with the sole surface of the last heel portion, the opposite surface of said forepart and the opposite surface of said back part being contoured to conform to the bottom surface of an insole to be inserted in the finished shoe when removed from the last.

8. An article in accordance with claim 7 which further includes a heel plate disposed on said opposite surface of said back part.
